CLAIM

The ornamental design for a triage/disaster management system bag, as shown and described.

DESCRIPTION

FIG. 1 is a perspective view of a triage/disaster management system bag showing my new design;

FIG. 2 is a front elevational view thereof;

FIG. 3 is a right side elevational view, the left side being a mirror image thereof;

FIG. 4 is a bottom view thereof; and

FIG. 5 is a perspective view of the triage/disaster management system bag in open position.

FIG.1

FIG.2

FIG.3
